J. H. GOODFELLOW,
BOILER FLUE SCRAPER.
APPLICATION FILED NOV. 22, 1920.

1,400,951.

Patented Dec. 20, 1921.

UNITED STATES PATENT OFFICE.

JOHN H. GOODFELLOW, OF BUFFALO, NEW YORK.

BOILER-FLUE SCRAPER.

1,400,951.

Specification of Letters Patent. Patented Dec. 20, 1921.

Application filed November 22, 1920. Serial No. 425,826.

To all whom it may concern:

Be it known that I, JOHN H. GOODFELLOW, a citizen of the United States, residing at Buffalo, in the county of Erie and State of New York, have invented new and useful Improvements in Boiler-Flue Scrapers, of which the following is a specification.

This invention relates to boiler flue scrapers.

10 The principal object of this invention is to provide a scraper of this character which is simple and light in its construction; which is durable and efficient in operation; and which can be manufactured at a low cost.

15 Another object is to so construct the scraper that its blades or cutters are adjustable to fit different sized flues.

Another object is to provide means for preventing the rear end of the scraper from dropping out of central line, and to also support the scraper centrally from the end of the rod after it has passed through and beyond the end of the tube, thus assuring the true wearing away of the cutters, and preventing any cramping of them during travel through the tube.

20 A final object is to construct such a scraper so that it will have extreme flexibility within a set diameter, and at the same time be prevented from increasing lateral friction upon the tube while working against the crust therein.

In the accompanying drawings:

Figure 1 is a side elevation of my improved flue scraper positioned in a section of boiler tube shown in section. Fig. 2 is an enlarged longitudinal section thereof, illustrating detail construction and operation.

Fig. 3 is a front view thereof at 3—3, Fig. 1.

40 Fig. 4 is an enlarged transverse section on line 4—4, Fig. 1. Fig. 5 is a vertical transverse section on line 5—5, Fig. 2. Fig. 6 is an end view of the scraper support shown at the right hand end of Fig. 1.

45 Heretofore it has been the prevailing method to construct a scraper with the blades or cutters held or pivoted at one end to a saddle which was made rigid to the shaft, and pivoted at their opposite ends to a flexible connection for expanding and contracting the cutters, while others had a central screw shaft upon which were nuts having shoulders to engage the cutter bars to effect an expansion. Still others brought about an

50 expansion by compressing the ends toward each other, causing the center of the cutter

bars to bulge outward, in which method there was very little yieldability in their action in going through a tube.

All of these types of flue scrapers, when attached to an operating rod invariably would wear away on one side, because the rod was bent, usually caused by its buckling under pressure.

And in others, where the cutters are expanded by a spring on the front end operating against toggle joints, all of the joints are compressed simultaneously, so that if one cutter contacts a blister, all of the cutters likewise yield, making a ridge corresponding with the said blister of unremoved scale.

In all of these types of flue scrapers, particularly of the single end type, the rear ends were provided with what are known as incline riders, by which means the cleaner could be drawn back into the flue after it has passed beyond the rear end and dropped down onto the rod; then by what is termed bouncing the scraper by a series of jerks on the rod would restore it to the tube. All of this action frequently damaged the scraper and weakened the end of the tubes. Furthermore the fact that the scraper has the usual long length of rod behind it would provide weight and leverage to bear down the rear end of the scraper, so it would go through the tube in a universally-tiltable manner. This rocking or side flopping would quickly destroy any cutting edge, and if it had any, when new, would be quickly destroyed, and then again this rocking is caused by going over blisters and causes violent cramping of the tool in the tube.

Whereas in my construction I have designed to overcome all of these disadvantages, and produce a scraper which will have extreme flexibility inside of a set diameter, and always the same under high or low compression which does not exist in scrapers heretofore made, and furthermore I provide a new method in reciprocating the scraper saddle and blades longitudinally and rotating them upon the shaft to effect these changed conditions, and I furthermore provide a practical means as an extension of the rear end which fully meets the demand of always maintaining the scraper centrally in the tube and prevents any cramping therein, and further supports it centrally to return to the tube after it has passed through and beyond the tube, without any of the defects I have sighted.

Similar characters of reference indicate corresponding parts throughout the several views.

10 indicates the central shaft or spindle 5 of the scraper which is preferably constructed of steel rod, being uniform diameter throughout its length, and having a suitable screw thread 11 at its rear end extending about one-third of its length. A 10 stop 12, preferable consisting of a suitable collar is positioned near the front end of the shaft, as shown and held thereto by a suitable pin 13.

Secured to the front end of the shaft is a 15 suitable bell-shaped member 14 preferably of cast metal which may be secured thereto by a pin 15, the depth and diameter of the bell portion 16 to be sufficient for the requirements and proportion of the size of 20 scrapers with which it is used. The object of this bell-shaped member is to provide a circular housing, to regulate the possible diameter of expansion of the cutter arms, to provide a chamber in which the horns may 25 freely vibrate between its outer edge, and the shaft and to permit their escape as shown by dotted lines Fig. 2. The numeral 17 represents an open coil spring positioned on the said shaft in front of said stop, and 30 of sufficient length to actuate the scraper saddle into normal position. A tube or sleeve 18, of suitable length and freely 35 slidable and rotatable upon the said shaft, is provided with an external screw thread 19 with which a corresponding bore 20 of the saddle 21 engages. The forward end of this sleeve is provided with a plurality of radial slits or grooves 22, extending longitudinally 40 of a part of its forward length, there being three equally spaced slits shown in the drawings, the office of these slits or grooves being to seat the spring resting therein, see 45 5—5, Figs. 2 and 5.

The numeral 23 represents a loose spacing 45 tube adapted to engage the inside of the operating nut 24 having preferably an enlarged bell-shaped portion 25, and also an internal screw thread 26 for engagement with the thread 11 of the shaft 10. 27 is a 50 jam nut to engage the rear of the bell-shaped nut; 28 is an ordinary reducing connection, and 29 is a supplementary extension to the shaft 10, serving as a handle for the device.

55 The supporting saddle 21 which carries the cutters, as shown in this instance, is provided with three pairs of radial bifurcated lugs or ears 31, preferably of cast metal and integral with the saddle 21 and equally disposed thereon as shown in Figs. 4 and 5.

The numeral 35 represents the scraper blades or cutters each of which is of cast metal, preferably cast or malleable iron, and preferably of the form and contour or design shown in the drawings. Each of these

arms is pivoted at 36 between a corresponding set of lugs 31 on the saddle 21. Each blade is composed of two forwardly spreading V-shaped arms 37, 37, the forward ends being joined to the arched cutter head 38, 70 which is shown beveled inward and rearwardly on its front face, see Figs. 1 and 3, while its rear wall 39 is correspondingly counter arched, and diametrically opposite their adjoining parts are wings 40 which 75 are alternately offset so that each will overlap the adjoining cutter wing as shown in Figs. 1 and 4, when the blades are fully compressed around the operating shaft, and thus aid in preventing any soot passing between 80 them.

The forward end of each scraper blade is provided with a forwardly inclined horn 41 its forward end being adapted to engage the inside portion 16 of the bell-shaped member 85 14. The object of this horn is to depress the scraper blade and maintain any set diameter desired.

Arranged in the rear wall of the arched head 38 is an opening 42. 43 represents a 90 rectangular housing arranged at the apex of the bifurcated arms 37 just in front of the pivot 36, the side walls of which are fashioned to fit closely the width of the coil 95 49 of a spring 50, see Fig. 5, and the external 100 outside walls have bosses 44, through which a cotter pin 46 passes for supporting the spring in position therein, as shown.

The spring 50 is provided with an upper 105 arched arm 48 which engages the hole 42 in the head 38 and a lower arm 51 which is provided with an upturned end, the bow of which is adapted to engage with the corresponding slit 22 in the sleeve 18. Thus it will be seen that the said spring becomes 110 double active whenever the scraper blades are moved in active position to have its horns within the bell-shaped member 14 and is also capable of removal or renewal by the adjustment of the cotter pin 46.

When it is desired to remove the scraper blades 35 the member 25 is turned upon the shaft 10 until the coil spring 17 has pushed the sleeve 18 and blades back sufficient to allow the horns to escape from the controlling bell-shaped member 14, as shown by dotted lines in Fig. 2, at which time any renewal or change can be made.

When these scraper blades are disengaged 120 from the bell shaped member 14 they will swing wide open about their pivots under the tension of the springs 50. By compressing them toward the shaft and by turning the rear bell 25 clockwise the sleeve 18 is moved forwardly together with the saddle 21 and blades 35, thereby compressing the spring 17 and storing up power for retraction when needed. As soon as the front ends of the horns 41 are within the forward bell-shaped member the blades are com- 125 130

pressed to any desired size. It is to be observed that no pressure on the front of the blades can affect any undue friction on the interior of the tube being acted upon, so 5 that the tremendous expansion obtained by this method assures durability of the parts.

Another point of advantage is observed in the fact that the scraper, having been set to go through a tube at a diameter a little 10 less than the actual diameter, goes through at that without any undue friction, yet, at the same time, as the scraper wears away the enlargement is made by turning the rear bell-shaped member to the left, and by setting the jam nut, will remain so.

By referring to Figs. 1 and 6, I have shown my improved method of doing two additional things; namely, grinding the scraper blades parallel and true, and at 20 the same time preventing any cramping or wabbling of the rear end of the scraper in the tube, while going through, particularly of the single end type of scraper. I attain this result by extending the rear screw 25 shaft, preferably by providing the disconnecting supplementary extension 29 on which is positioned a suitable sleeve 52 secured to said section by a pin 53 or any means that will locate it at a safe distance 30 from the scraper.

This sleeve is provided with radial wings 54 having outer edges 55 preferably chilled as hard as possible and well rounded so that they may move through the soot with edge- 35 wise cleaving, and thus support the scraper rod centrally within the flue.

I claim as my invention:

1. A boiler flue scraper, comprising a shaft, a saddle slidable lengthwise on said 40 shaft, scraper blades pivoted at one end to said saddle and capable of independent yieldable movement, the other ends of said blades being provided with forwardly tapering horns, a bell-shaped member mounted 45 on said shaft in front of said saddle and cooperating with the horns of said blades for contracting them upon the movement of said saddle toward said bell-shaped member, and means for permitting expansion of said 50 blades when said saddle is moved in the opposite direction.

2. A boiler flue scraper comprising a shaft, a sleeve arranged on the latter and movable lengthwise thereon, a saddle mounted 55 on said sleeve, scraper blades pivoted to said saddle and capable of expanding and contracting relatively to said shaft, controlling means fixed to said shaft and adapted to engage the free ends of said scraper 60 blades, and means for imparting movement to said sleeve whereby said blades are moved toward and from said controlling means.

3. A boiler flue scraper comprising a shaft, a sleeve arranged on the latter and 65 movable lengthwise thereon, a saddle mount-

ed on said sleeve, scraper blades pivoted to said saddle and capable of expanding and contracting relatively to said shaft, controlling means fixed to said shaft and adapted to engage the free ends of said scraper blades, 70 means tending to resist contraction of said blades, and means for imparting movement to said sleeve whereby said blades are moved toward and from said controlling means.

4. A boiler flue scraper comprising a 75 shaft, a sleeve arranged on the latter and movable lengthwise thereon, a saddle mounted on said sleeve, scraper blades pivoted to said saddle and capable of expanding and contracting relatively to said shaft, a bell- 80 shaped member cooperating with the free ends of said blades, means connected with said shaft for imparting movement to said sleeve whereby said blades are moved toward said bell-shaped member, and means 85 resisting the forward movement of said sleeve.

5. A boiler flue scraper comprising a shaft, a saddle movable lengthwise thereon, scraper blades carried by said saddle and capable of 90 expanding and contracting relatively to said shaft, a bell-shaped member fixed to said shaft and adapted to engage the free ends of said scraper blades, means movable on said shaft for imparting movement to said 95 saddle whereby said blades are moved toward said bell-shaped member, and a coil spring between said saddle and said bell-shaped member for resisting such movement.

6. A boiler flue scraper comprising a shaft 100 having a threaded portion, a saddle arranged on the latter and movable lengthwise thereon, scraper blades pivotally mounted on said saddle, a bell-shaped member fixed on said shaft and adapted to engage the free 105 ends of said blades, a screw nut engaging the threaded portion of said shaft for moving said saddle toward said bell-shaped member, and a spring on said shaft tending to move said saddle in the opposite direction. 110

7. A boiler flue scraper comprising a shaft having a threaded portion, a bell-shaped member secured at one end of the shaft, a saddle arranged on the latter and movable lengthwise thereon, scraper blades pivotally 115 mounted on said saddle, the free ends of said blades tapering forwardly and adapted for engagement with said bell-shaped member, an adjustable member engaging the threaded portion of said shaft for moving said saddle toward said bell-shaped member, means arranged on said shaft between said saddle and said bell-shaped member for resisting the forward movement of said saddle, and means constantly tending to move said 120 scraper blades outwardly relatively to said shaft.

8. A boiler flue scraper comprising a shaft, a saddle movable lengthwise thereon, scraper blades having forwardly spreading V-shaped 130

arms pivotally mounted on said saddle, means on said shaft for contracting said blades when said saddle is moved in one direction, and a coil spring having forwardly 5 extending legs carried by each of said blades, the coil of said spring being arranged between the rear connected ends of the arms of each blade and the legs thereof engaging said shaft and said blade respectively, where- 10 by they are expanded when said saddle is moved in the opposite direction.

9. A boiler flue scraper comprising a shaft, a sleeve having radial slots rotatably mounted on said shaft and movable lengthwise 15 thereon, a saddle mounted on said sleeve, scraper blades pivoted to said saddle and

capable of expanding and contracting relatively to said shaft, a bell-shaped member coöperating with the free ends of said blades, means connected with said shaft for imparting movement to said sleeve whereby said blades are moved toward said bell-shaped member, means resisting the forward movement of said sleeve, and a coil spring having forwardly extending legs carried by said 25 blades, one leg of each of said springs being seated in a slot in said sleeve and the other leg engaging the front end of its blade.

Signed at Buffalo, in the county of Erie and State of New York, this 19th day of 30 Nov. A. D. 1920.

JOHN H. GOODFELLOW.
